MONTFORD MORRISON, OF NEW YORK, N. Y., ASSIGNOR TO WESTINGHOUSE ELECTRIC
AND MANUFACTURING COMPANY, A CORPORATION OF PENNSYLVANIA

X-RAY TUBE

Application filed June 9, 1922. Serial No. 566,961.

My present invention relates to X-ray tubes.

An object of this invention is the provision of an X-ray tube which may be operated with substantial positive ionization of the gas within the tube.

Another object of this invention is the provision of a focusing device which will aid in suppressing ionization of the residual gas in an X-ray tube.

Other objects of the invention may be perceived from a reading of the following specification.

In the operation of X-ray tubes employing a hot cathode, the occurrence of a considerable amount of ionization of the residual gas gives rise to several deleterious effects which are well known. One method proposed for avoiding such effects is the evacuation of the tube to the highest possible degree. To obtain such a degree of vacuum is not only an unnecessarily prolonged process but such a vacuum, when attained, is difficult to maintain during the life of the tube. Moreover, at the high voltages now in use, a certain amount of the undesired ionization is obtained even in a so-called high vacuum. This ionization inevitably results from the structure given certain members of the device. For example, the existence of sharp points or edges having small radii of curvature on such elements as the anode and the focusing device has been found to be responsible for at least part of the gaseous ionization. That this is true may be realized when it is considered that the intensity of an electric field or potential gradient is greater at a sharp point or edge than at a surface having large radii of curvature and that the liability of obtaining ionization is greater the higher the potential gradient or intensity of the electric field.

I, therefore, propose an X-ray tube in which sharp points or edges and surfaces of small radii of curvature shall be eliminated from those parts of the tube where such configurations may give rise to intense electric fields which cause gaseous ionization. Accordingly, the present invention comprises a focusing device and an anode characterized by the absence of sharp points or edges and

the substitution therefor of curved surfaces having such radii of curvature that the intensity of the electric field may be reduced to a value at which no substantial amount of gaseous ionization results, or at least to a point at which ionization plays no essential role in the production of X-rays. The comparatively low intensity of the electric field produced by my invention allows a higher gas pressure to exist in the tube so that there is no necessity for attaining and maintaining the extremely high vacuum so desirable in tubes of the prior art.

In the accompanying drawings illustrating my invention,

Fig. 1 is an elevational view, partly in section, of an X-ray tube embodying the novel form of focusing device surrounding an incandescent filamentary cathode; and,

Fig. 2 is a plan view of a toroidal focusing device and a spirally-wound cathode taken on line II-II in Fig. 1.

An illustration of my invention is shown in the accompanying drawing which is a view in elevation, partly in section, of an X-ray tube comprising a spherical evacuated glass envelope 2 having oppositely extending arms 3 and 4 into which are sealed, respectively, an anode 5 and a cathode 6, the former having a leading-in conductor 7 and the latter having leading-in conductors 8 and 9. The leading-in conductors of both electrodes and the inactive parts of the electrodes themselves are preferably covered with an insulating material. Encircling the cathode 6 is a focusing device 11 for the purpose of concentrating the cathode rays into a limited area.

The feature of the anode 5 resides in its form, which, as illustrated in the drawing, is that of a spheroid, although it may take other forms embodying surfaces having large radii of curvature with the elimination of sharp points or edges. The material used in the construction of the anode 5 may be the same as that usually employed.

Opposite the anode or target 5 is the cathode 6 which may be a spiral of refractory conducting material such as tungsten so that it may be heated to an electron-emitting temperature. Encircling the cathode 6, the fo-

cusing device 11 is shown as a solid ring or toroid, the novel feature of which consists in its having a form devoid of sharp points or edges and characterized by surfaces having comparatively large radii of curvature.

5 The focusing device 11 may be supported by a hollow cylinder 12, one end of which is secured to the focusing device 11, the other end being fitted securely over the glass stem

10 14. As usual, the focusing device 11 and its extension 12, both of which consist of conducting material, are electrically connected to the cathode, which is shown in the drawing by a wire 15 connecting the leading-in 15 conductor 9 to the extension 12.

In the preparation of the tube, the envelope should be exhausted of gases and vapors, means for accomplishing which are well known in the art. The component parts of 20 the X-ray device, particularly the anode and focusing device, should also be freed from gases and vapors; this may be accomplished, for example, by heating the device to a high 25 temperature in a vacuum and removing the released gases and vapors. The degree of vacuum to which the tube is evacuated or the pressure of the gas admitted should be such that no substantial amount of ionization will occur during the operation of the tube.

30 30. The presence of gas sufficient to cause positive ionization which will be harmful to the tube may be recognized by the form of the voltage-current curve and by other means known to those skilled in the art, whereby 35 the presence of a deleterious amount of gaseous ionization may be detected.

While I have herein described a preferred 40 embodiment of my invention, it is to be understood that modifications of the same may be contrived without departing from the scope thereof, as defined by the appended claims.

What is claimed is:

1. An X-ray tube comprising an evacuated 45 envelope, an electron-emitting cathode and an anode therein, and a focusing device surrounding said cathode, said focusing device having a curved surface facing said anode and extending above and below said cathode.

50 2. An X-ray tube comprising an evacuated envelope, an electron-emitting cathode and an anode therein, and a focusing device surrounding said cathode, the exposed surface of said focusing device being curved to a degree at which the intensity of the electrical field at the surface is reduced sufficiently to avoid objectionable concentration, whereby the liability of gaseous ionization occurring is materially reduced.

60 3. An X-ray tube comprising an evacuated envelope, an electron-emitting cathode and an anode therein, a focusing device for controlling the direction of the cathode rays, said focusing device having its exposed surface so curved that the intensity of the elec-

trical field at the surface is reduced sufficiently to avoid objectionable concentration, whereby the liability of gaseous ionization occurring is materially reduced.

4. An X-ray tube comprising an evacuated 70 envelope, an electron-emitting cathode and focusing device therefor, and an anode, the exposed surface of said anode being so curved that the electrical field at the surface is reduced sufficiently to avoid objectionable 75 concentration, whereby the liability of gaseous ionization occurring is materially reduced.

5. An electron discharge device comprising an evacuated envelope and a plurality of electrodes therein, the exposed surfaces of said electrodes being so curved that the electrical fields at the surfaces thereof are reduced sufficient to avoid objectionable concentration, whereby the liability of gaseous 85 ionization occurring is materially reduced.

6. An X-ray tube comprising an evacuated 90 envelope, an electron-emitting cathode and an anode therein, and a focusing device for controlling the direction of the cathode 95 rays, said focusing device and anode having their exposed surfaces so curved that the electrical fields at the surfaces thereof are reduced sufficient to avoid objectionable concentration, whereby the liability of gaseous 100 ionization occurring is materially reduced.

7. An electron discharge device comprising an evacuated envelope and a plurality of electrodes therein, the exposed surface of one of said electrodes being so curved that the electrical fields at the surface thereof are reduced sufficiently to avoid objectionable concentration, whereby the liability of gaseous 105 ionization occurring is materially reduced.

8. A discharge device comprising an hermetically sealed envelope and at least one electrode extending toward the interior of said envelope from which a discharge takes place under normal conditions of operation, 110 the end of said electrode presented to the interior of the envelope having a degree of curvature of such magnitude as to distribute the electrostatic fields about the same uniformly thereover.

115 9. A discharge device comprising an hermetically sealed envelope and a plurality of electrodes thereon between which a discharge takes place under normal conditions of operation, one of said electrodes being substantially wholly convex and non-focusing, whereby the concentration of electrostatic fields thereabout is substantially prevented.

120 10. A discharge device comprising an hermetically sealed container and at least one electrode presented to the interior of said container from which a discharge takes place under normal conditions of operation, said 125

electrode being so curved as to prevent any localized gaseous ionization occurring and reaching a large value.

In testimony whereof, I have hereunto
5 subscribed by name this seventh day of June,
1922.
